Primary Examiner — Jonathan J Han*Assistant Examiner* — Christen Pilar Brown-Lorrig(74) *Attorney, Agent, or Firm* — Asgaard Patent Services, LLC; F. Wayne Thompson, Jr.(57) **CLAIM**

The ornamental design for a shoelace, as shown and described.

DESCRIPTION

FIG. 1 is a perspective view of a shoelace, showing my new design;

FIG. 2 is another perspective view of the shoelace shown in FIG. 1;

FIG. 3 is a front elevational view of the shoelace shown in FIG. 1;

FIG. 4 is a right side elevational view of the shoelace shown in FIG. 1;

FIG. 5 is a leftside elevational view of the shoelace shown in FIG. 1;

FIG. 6 is a rear elevational view of the shoelace shown in FIG. 1;

FIG. 7 is a top plan view of the shoelace shown in FIG. 1;

FIG. 8 is a bottom plan view of the shoelace shown in FIG. 1; and,

FIG. 9 is a perspective view of the shoelace shown in FIG. 1, depicted on a shoe.

The broken lines shown in FIG. 9 are included for the purpose of illustrating environment that forms no part of the claimed design.

1 Claim, 5 Drawing Sheets(56)
